J.C. Ryan,

UNITED STATES PATENT OFFICE.

JOHN C. RYAN, OF CROSBY, TEXAS.

ATTACHMENT FOR ROCKING-CHAIRS.

1,072,995.

Specification of Letters Patent. Patented Sept. 9, 1913.

Application filed August 31, 1912. Serial No. 718,166.

To all whom it may concern:

Be it known that I, JOHN C. RYAN, a citizen of the United States, residing at Crosby, in the county of Harris and State of Texas, have invented certain new and useful Improvements in Attachments for Rocking-Chairs, of which the following is a specification, reference being had to the accompanying drawings.

10 This invention relates to fan attachments for rocking chairs and has for its primary object to provide a simple mechanism for actuating a rotary fan, said mechanism being operated in one direction of movement 15 of the rockers of the chair.

Another object of the invention is to provide a platform or supporting base having grooves to receive the rockers of the chair, said base and the chair rockers being provided with means to prevent longitudinal movement of the chair upon said base, a frame mounted upon the base and a fan arranged in the frame, mechanism mounted on the base for rotating the fan shaft, and 25 means carried by the chair rockers to actuate said mechanism.

Still another object of the invention is to provide a fan actuating mechanism which consists of comparatively few elements of 30 simple form whereby a mechanism is produced which is reliable and positive in operation and is capable of manufacture at comparatively small cost.

With the above and other objects in view 35 the invention consists in the novel features of construction and the combination and arrangement of parts hereinafter more fully described, pointed out in the claim and shown in the accompanying drawings in 40 which,

Figure 1 is a side elevation of a fan attachment for rocking chairs embodying the present invention. Fig. 2 is a top plan view. Fig. 3 is a section taken on the line 3—3 of 45 Fig. 2, and Fig. 4 is a rear elevation.

Referring in detail to the drawing, 5 designates a base or platform upon which the rocking chair indicated at 6 is arranged. This chair includes the usual curved rockers 50 7 which are disposed in parallel longitudinal grooves or channels 8 formed in the upper surface of the base or platform 5. A rack 9 is secured in each of these grooves or channels and complementary racks 10 fixed 55 to the under surfaces of the rockers 7 mesh with the teeth of the racks 9 and effectively

prevent longitudinal sliding movement of the chair rockers in the grooves of the platform. These grooves are of sufficient depth to obviate liability of the chair rockers moving transversely upon the platform out of 60 said grooves.

Upon the base or platform 5 a suitable frame structure 11 is erected, and is firmly braced by means of the rods 11' which extend through the base 5. Upon each side of the frame 11 a transversely disposed fan shaft 12 is journaled in suitable bearings 13. Upon each of the shafts 12 a fan 14 of any approved form is secured. These fans are 65 inclosed within a skeleton frame or casing 15 to protect the occupant of the chair against possible injury by contact of the fingers with the fan blades.

Upon the rear end of the platform 5, a 70 shaft 16 is rotatably mounted. This shaft has fixed upon each end a pulley or belt wheel 17. These wheels are traversed by the endless belts 18 which extend upwardly and pass around the pulleys 19 fixed upon 75 the fan shafts 12. Upon the shaft 16 a gear 20 is loosely mounted and adjacent to this gear a ratchet 21 is fixed upon said shaft. Upon one face of the gear 20 a pawl 22 is pivotally mounted and is adapted to engage 80 with the teeth of the ratchet 21 to lock the loosely mounted gear 20 upon the shaft 16 to rotate said shaft in one direction. Upon 85 the rear end of one of the rockers 7 a curved downwardly extending rack 23 is secured. The teeth of this rack mesh with the teeth 90 of the gear 20.

As above described, the operation of the invention will be understood as follows: When the rear ends of the rocker move 95 downwardly in the backward rocking movement of the chair upon the platform, the rack 23 on the chair rocker meshing with the gear 20 on the shaft 16 rotates said shaft, the gear 20 being locked upon the 100 shaft by means of the ratchet and pawl 22. Thus rotary movement is transmitted to the fan shafts 12 through the medium of the belts 18, and the fans create a circulation 105 of air in the vicinity of the chair.

The fan shafts 12 are preferably mounted on about a level with the shoulders of the chair occupant.

In order to hold the teeth of the racks 9 and 10 in mesh, I provide one or more heavy 110 coil springs 24 which are fixed at one of their ends to the platform 5 and at their

ends to a cross bar connecting the rockers 7. In the forward movement of the chair, the rack 23 carried by the rocker thereof moves upwardly and the gear 20 rotates 5 upon the shaft 16 independently thereof, the pawl 22 carried by said gear moving idly over the teeth of the ratchet 21.

From the foregoing it will be seen that I have devised a very simple and efficient fan 10 attachment for rocking chairs and operating means therefor, which, upon each backward movement of the chair will rotate the fan, thereby effecting a circulation of the air and conducing to the comfort of the occupant. As the device consists of comparatively few elements which are not liable to become easily deranged it will be apparent 15 that the mechanism is very durable in use and may be produced at small cost. The 20 device as a whole is very efficient and of great convenience and serviceability in practical use.

While I have shown and described the preferred construction and arrangement of 25 the various parts, it will be understood that the invention is susceptible of considerable

modification without departing from the essential features or sacrificing any of the advantages thereof.

What I claim is:—

In a device of the character described, the combination of a platform, a rocking chair mounted thereon, a support arranged on the platform adjacent to the chair, a shaft journaled upon said support, a fan secured to 30 said shaft, operating means for said shaft mounted upon the platform, said means including a gear and a power transmitting connection between said operating means and the fan shaft, and a curved rack bar 35 fixed at one of its ends to the rear end of one of the chair rockers and extending below the same to coact with said gear and actuate the operating means in the rocking movement of the chair in one direction. 40

In testimony whereof I hereunto affix my signature in the presence of two witnesses.

JOHN C. RYAN.
